UNITED STATES PATENT OFFICE.

ROBERT R. McCORMICK, OF CHICAGO, ILLINOIS.

PRINTING PRESS.

Application filed September 2, 1924. Serial No. 735,269.

To all whom it may concern:

Be it known that I, ROBERT R. McCORMICK, a citizen of the United States, residing in Chicago, in the county of Cook and State of Illinois, have invented certain new and useful Improvements in Printing Presses, of which the following is a specification.

This invention relates to a press for printing newspapers and the like, and more particularly to a novel arrangement of printing units and web associating mechanism, for effecting practically any desired association of printed pages with the possible utilization at all times of the maximum number of printing couples under all the variant associations of the pages.

Heretofore, in the operation of presses for printing newspapers, uncalled for losses have been occasioned by the enforced idleness of certain of the printing couples or units when it became necessary to print sections or parts of the paper containing a different number of pages than usual. This was due to the fact that the separate presses in the press room were disposed in isolated groups and were not arranged so that the webs from the printing couples or units of each press could be associated with each other. In other words, each press was capable of printing its own capacity of pages and could not be increased beyond that.

One of the objects of my invention resides in providing a press comprising a plurality of printing and folding units arranged on a common horizontal plane or printing level, the printing units being suitably spaced apart in a single, relatively long, line or row, whereby to provide accessibility and facility in the printing and folding operations, and the printing and folding units being arranged in such a manner that the printing units may be associated in various arrangements including octuples, decuples and double sextuples with the utilization of the maximum number of printing and folding units under all conditions of association.

A further feature of the invention resides in the arrangement of a relatively large number of printing couples such as thirty couples, in a single row and on a common printing level on a supporting frame, and in the disposition of the folders in the printing level intermediate certain of the printing couples, together with guide rolls where-

by a flexible press for effecting any practical association of the pages is secured.

Yet another object of the invention resides in the novel arrangement of the multiple units as hereinbefore described together with upper and lower pairs of formers intermediate certain of the printing units and in the relation and disposition of the guide rolls and folders therefor, whereby the webs from the units or couples can be associated selectively on the upper or lower pair of formers or on both of said pairs of formers. This arrangement is particularly advantageous in that it permits great flexibility of the page associations from the various units which is essential to the every day demands on the press because of the constantly changing associations being printed on the same press for the different issues and editions of the paper. These and other objects of the invention will be apparent from a perusal of the following specification when taken in connection with the accompanying drawings wherein:

Figure 1 is a rather diagrammatic view of the complete flexible unit press, showing the printing couples and folders arranged to associate the units in octuples.

Figure 2, is a similar view of the press showing the conversion or rearrangement of the units and associating devices for printing in decuples.

Figure 3 is still another arrangement showing the associating mechanism arranged to print in double sextuples.

Figure 4 shows the flexibility of the press for various arrangements.

Figure 5 is an enlarged view of that portion of the press shown in Figure 1 disclosing the first octuple.

Figure 6 is a similar view disclosing the diversion of a portion of the webs from the couples to the upper former of the intermediate folding mechanism.

And, Figures 7 and 8 are rather diagrammatic disclosures of the arrangement of the upper and lower formers and folders.

Referring now to the drawings in detail, the press comprises the relatively long frame or support 50 upon which the printing couples or units and associating devices including the folders and guide rolls are mounted. As shown clearly in Figure 5, the main frame is preferably supported in elevated position to provide a separate level for the

web supply rolls 51. The frames 52 for the printing couples 53, and the driving mechanism 54 therefore are mounted on top of the main frame 50. At desired locations, 5 longitudinally of the frame 50, suitable frames 52 support folding mechanisms or units including pairs of formers. The folding units are arranged in line with the printing units and are suitably spaced apart 10 therefrom to provide accessibility. These frames 52 and other suitable frames extend upwardly as at 57, to support feed rolls 55, and formers 56 which are arranged over the lower pair of formers. The upstanding 15 frame extensions 57 are also provided with angle bars and other usual feeding devices. By means of this arrangement, the printing and folding units are disposed in a single or common printing level so that a single 20 press crew can handle the printing and folding operations.

In the present invention, the preferred practical arrangement for providing flexibility consists in disposing at least thirty 25 printing couples or units 53 in series or tandem longitudinally on the support 50. The cylinders are preferably double width so that with the full wide web, each couple is capable of printing sixteen pages, preferably two sets of eight pages each. Other arrangements and narrower webs, are, however, within the contemplation of the invention. The folding mechanisms are disposed to operate intermediate certain of these 30 printing units, and the most practical disposition is that shown in the drawings wherein it will be noticed that the first folding mechanism is located between the third and fourth printing units or couples; the 35 second folding mechanism is located between the ninth and tenth printing couples; the third folding mechanism is located between the twelfth and thirteenth printing couples; the fourth folding mechanism is 40 located between the fifteenth and sixteenth printing couples; the fifth folding mechanism is located between the eighteenth and nineteenth printing couples; the sixth folding mechanism is located between the 45 twenty-first and twenty-second printing couples, and the seventh folding mechanism is located between the twenty-seventh and twenty-eighth printing couples or units.

In order to supply these printing couples 55 with paper, the web supply rolls 51 are arranged substantially beneath the printing couples, there being thirty of them, one set for each couple, and any desired arrangement of guide rolls 58 is provided on the 60 frame 50 for directing the webs from the supply rolls to the printing couples. The control mechanism 54 for independently controlling the driving operation of each set of printing couples is also mounted on the frame 50. Inasmuch as this driving

mechanism forms no part of the present invention other than as a means to independently connect or disconnect any desired printing couple, it is not shown in detail.

It must be manifest from an understanding of the foregoing and a study of the drawings, that the press is capable of printing various associations of pages. For instance, in Figure 1 the webs are directed and associated for printing with the units arranged in octuples, there being seven of such octuples. In this arrangement the first printing couple is thrown out of operation. An inspection of Figure 5 will reveal in greater detail the direction and paths of the webs from the various couples and the particular guide rolls which are used for the octuple arrangement of the units. The guide rolls 60 assist in directing the web from the supply rolls to the printing cylinders so that the direction of travel of the web to the printing cylinders may be reversed. The two paths of travel of the paper web are disclosed in Figure 1 of the drawings, for instance, see printing couples two and seventeen. In Figure 5 it will be noticed that the webs from all of the couples are directed by the guide rolls to the lower pair of formers of folding mechanism 1. Thus, in the preferred arrangement, folding mechanism 1 associates per revolution, two complete papers having two sections, both sections being composed of thirty-two pages.

From an inspection of Figure 6 it will be manifest that other page associations can be obtained when the units are arranged in octuple. Here the webs from couples two and three are directed by the upper guide rolls, to the upper pair of formers of folding mechanism 1 and the webs from the couples four and five are directed, as in Figure 5, to the lower pair of formers of folding mechanism 1. In this modified arrangement, four sections of eight pages each are associated. It must be obvious that practically any other associations both with double wide cylinders and webs and narrower cylinders and webs are capable of being effected, with the use of these twenty-eight operative printing couples; it being remembered that two of the printing couples or units are idle in this arrangement.

The printing couples and folders are also capable of being arranged as set forth in Figure 2. Here the units are printing and associating as decuples, there being six decuples. All thirty of the printing couples are now used. In this arrangement folding mechanism number four is idle. But all of the printing units are operative.

In the decuple arrangement, with double wide cylinders and double wide webs, each decuple is capable of printing two complete

papers of forty pages each per revolution. The pages can be associated as two sections of twenty pages each or any four page variation thereof. With one-half and three-fourths wide webs any two page or combined two and four page variation can be delivered. This arrangement can be secured because the pages are printed two on, which means that each type cylinder duplicates the type impression or prints two sets of four pages each. In this way a two page variation can be obtained.

Figure 3 shows still another disposition of the associating means and units, to print and associate as double sextuples, that is, with forty-eight pages to a delivery. This is the maximum number of pages which the cutting mechanism can operate successfully upon and is hence the practical associating limit of the press in so far as the cutting only is concerned. It will be noticed in the arrangement shown in Figure 3, that all the printing units are operative but that folding mechanisms number three and five are idle. It is clear that with these arrangements disclosed in Figures 2 and 3 the webs can likewise be directed so as to fold over either the upper or lower pairs of formers or over both as illustrated in Figure 6. The superimposed arrangement of formers and folders permits of great flexibility of association and adaptability with regard to inter-folding of the sections from the units.

In the double sextuple arrangement disclosed in Figure 3, one double sextuple is capable of printing, per revolution, two complete papers of forty-eight pages each, or in two sections of twenty-four pages each, or these forty-eight pages can be associated in sections with variations of four pages, if upper formers are used, such for instance as three sections folded together, two sections containing twenty pages each and the third section containing eight pages. Or there can be four interfolded sections of twelve pages each or three of sixteen. The manner of folding together three or four sections of a paper is diagrammatically illustrated in Figures 7 and 8 of the drawings, wherein the cut webs A, B, C and D from the printing units are conducted to the upper and lower formers 56 and are thence all folded together by the suitable folding mechanism. It is manifest that with one-half wide webs any variation of two pages or combinations of two and four pages can be associated.

Still another illustration of the flexibility of the press is disclosed in Figure 4 of the drawings wherein the units of the press are arranged in aggroupments of variant numbers of printing units each. Others still are possible.

From the foregoing description it must be clear that by thus providing a press com-

prised of such a series of units, in succession in a single line and with the folding mechanism thus disposed intermediate predetermined couples, a new flexible type of press is provided which assures the maximum utility of the various printing couples, and practically any desired combination of units and the association of any practical number of pages in a single press; that with this disposition of the cylinders of the printing couples so that their axes lie transverse to the length of the press and the arrangement of the folding mechanism in the longitudinal line of the units, the need for the usual angle bars is eliminated; that with this arrangement of the printing units and the upper and lower pairs of formers and the folders therefor any desired interfolding of sections can be secured, such as the folding together of three or four sections, and any variation in the number of pages to a section can be produced. It will be noted from the drawings that by means of my construction none of the webs passing from the printing units of any particular group to the folding unit of such group are compelled to pass across any other folding unit. Other valuable and practical features and advantages of this new arrangement will be obvious to those skilled in the art. And it is to be understood that the present invention is not to be limited to the exact details of construction or arrangement set forth in the drawings because such drawings are merely used as illustrative and not restrictive of the broad principles of the new features of construction and operation herein set forth.

Having thus described my invention, I claim:

1. A flexible unit press comprising a row of printing units accessibly arranged in spaced apart relation on the same printing level, a web supply for each unit, a plurality of folding units disposed on said printing level, said folding units being spaced apart and disposed relatively to said printing units so that the line of printing units is selectively divisible into a succession of equal groups of four, or five, or six printing units, 110 each selected group containing but a single folding unit and all of the printing units of a group of any selected series of groups feeding their webs to the folding unit of that group.

2. A flexible unit press comprising a single row of printing and folding units accessibly arranged in spaced apart relation on the same printing level, a web supply for each printing unit, said folding units being distributively arranged in said line and between said printing units so that the line of printing units is selectively divisible into a succession of equal groups of four, or five or six printing units, each selected group 120 125 130

containing but a single folding unit and all of the printing units of a group of any selected series of groups feeding their webs to the folding unit of that group whereby no web from a printing unit is compelled to travel across an idle folding unit.

3. A flexible-press for printing newspapers and the like comprising a supporting frame, thirty printing couples spaced thereon with their cylinders disposed transversely of and in a single row longitudinally of the frame and in a common plane, a plurality of folding mechanisms disposed on said frame in said plane intermediate and certain of said couples, said folding mechanisms being disposed between the third and fourth couples, and between the ninth and tenth couples, and between the twelfth and thirteenth couples, and between the fifteenth and sixteenth couples, and between the eighteenth and nineteenth couples, and between the twenty-first and twenty-second couples, and between the twenty-seventh and twenty-eighth couples, and guide-rolls on said frame for directing the webs from said couples to the folding mechanisms.

4. A flexible-press for printing newspapers and the like, comprising a supporting frame, thirty printing couples disposed in spaced relation in a common printing level 30 thereon with their cylinders disposed transversely of and in a single line or row longitudinally of the frame in the printing level and, pairs of formers disposed on said frame intermediate certain of said couples, said 35 pairs being disposed between the third and fourth couples, and between the ninth and tenth couples, and between the twelfth and thirteenth couples, and between the fifteenth and sixteenth couples, and between the 40 eighteenth and nineteenth couples, and between the twenty-first and twenty-second couples, and between the twenty-seventh and twenty-eighth couples, and guide rolls on said frame, said guide rolls and pairs of formers being constructed and arranged to direct the webs from certain of said couples to one or both of the formers of a pair or to one or both of said formers of said pairs.

In witness whereof, I hereunto subscribe 50 my name to this specification.

ROBERT R. McCORMICK.
